UNITED STATES PATENT OFFICE.

EDWARD C. LARKIN AND JOSEPH F. DUNCAN, OF DAYTON, OHIO.

COMPOUND AND METHOD OF INCREASING COMBUSTION OF COAL, &c.

1,017,677.

Specification of Letters Patent.

Patented Feb. 20, 1912.

No Drawing.

Application filed October 4, 1911. Serial No. 652,790.

To all whom it may concern:

Be it known that we, EDWARD C. LARKIN and JOSEPH F. DUNCAN, citizens of the United States, residing at Dayton, in the 5 county of Montgomery and State of Ohio, have invented certain new and useful Improvements in Compounds and Methods of Increasing Combustion of Coal, &c.; and we do declare the following to be a full, 10 clear, and exact description of the invention, such as will enable others skilled in the art to which it appertains to make and use the same.

Our invention relates to a new and useful 15 composition of matter for use in furnaces and like places to prevent the carbon in coal manifesting itself in smoke resulting from combustion.

The composition of matter may be produced in either a solid form, for example, 20 a powder, or it may partake of a liquid form. The latter we deem to be the most desirable because it can be administered more economically and efficiently in such 25 form.

The invention further consists in injecting heated compressed air for the purpose 30 of thoroughly sprinkling the solution over the fire and for supplying additional atmos-

The object of the invention is to provide for a more thorough elimination of smoke 35 by causing a more complete combustion of coal and the gases generated therefrom, and to reduce the destructive effect of the sulfur and other gases on the metal surfaces of the furnace exposed to the action of the heat.

We are aware that various chemicals have been compounded for the purpose of increasing 40 the combustion of coal and obviating the accumulation of smoke, many of which combined common salt with various other ingredients. It appears, however, that owing to the expensive character of these prior compounds 45 and the high degree of intelligence required in their use as well as other reasons, they have not met with success.

The liquid compound is made from the

following elements: common commercial salt, chemically named chlorid of sodium; 50 alum, and charcoal, preferably produced from willow wood, and water. Charcoal from willow wood has been found most satisfactory in actual use owing to its being capable of being reduced to a finer powder, 55 thereby serving as a better distributing agent or element in the composition.

In combining the above specified elements, the following proportions have been found to produce an agency which is highly 60 effective in causing the consumption of the carbon contained in a given quantity of fuel.

Chlorid of sodium	2 $\frac{3}{4}$	lbs.
Charcoal	$\frac{1}{4}$	lb.
Powdered alum	1	lb.
Water	1	gallon.

65

A gallon of the chemical compound as thus prepared is sufficient to treat a ton of coal. The solution is sprayed over the fire 70 as the coal is fed into the furnace. The injection of the solution is accompanied by an injection of previously heated air to thoroughly spray the solution over the fire and to introduce additional oxygen. The combined effect of the solution and air is to 75 instantaneously raise the temperature of the fire to a high degree, thereby burning all carbon and gases, and to preserve the metal of the furnace. After the solution has been 80 sprayed for a time, say one or two minutes, the effect is apparent. It may then be stopped and the injection of the air alone continued.

Having set forth our invention and the 85 manner of its use so that the best results may be obtained, we claim:

1. The herein described composition of matter, consisting of salt, alum, willow charcoal and water, combined in the proper 90 proportions, substantially as described and for the purposes specified.

2. The herein described method of increasing the combustion of coal and consuming carbon therein, which consists in injecting a solution of salt, alum, charcoal 95

and water, and in applying heated compressed air as a medium for the distribution of said solution over the fire at each charge of coal, and adding additional atmospheric 5 oxygen to the fire.

3. The herein described method of increasing the combustion of coal, which consists in spraying the coal with a solution of salt, alum, charcoal and water, in injecting 10 heated compressed air with said solution, and in stopping the injection of the solu-

tion and in permitting the injection of air to continue.

In testimony whereof we affix our signatures, in presence of two witnesses.

EDWARD C. LARKIN.
his
JOSEPH F. $\times$ DUNCAN.
